UNITED STATES PATENT OFFICE.

ALFRED W. REISER, OF TOLEDO, OHIO, ASSIGNOR TO THE REIDON COMPANY, OF
TOLEDO, OHIO, A CORPORATION OF OHIO.

DESIGN FOR A LINK FOR LIGHTING FIXTURES.

60,161.

Specification for Design.

Patented Jan. 3, 1922.

Application filed March 24, 1921. Serial No. 455,147. Term of patent 7 years.

To all whom it may concern:

Be it known that I, ALFRED W. REISER, a citizen of the United States, residing at Toledo, in the county of Lucas and State of Ohio, have invented a certain new, original, and ornamental Design for a Link for Lighting Fixtures, of which the following is a specification, reference being had to the accompanying drawing, forming part hereof.

Fig. 1 is a perspective view of a link for lighting fixtures embodying my new design.

Fig. 2 is a side view of the same.

I claim:

The ornamental design for a link for lighting fixtures, as shown.

ALFRED W. REISER.
